Robert J. Rader, New Rochelle, N. Y., assignor to
J. C. Penney Company, New York, N. Y., a cor-
poration of Delaware

Application June 12, 1935, Serial No. 57,234

Term of patent 7 years

To all whom it may concern:

Be it known that I, Robert J. Rader, a citizen of the United States, residing in New Rochelle, in the county of Westchester and State of New York, have invented a new, original, and ornamental Design for Velocipede Frame, of which the following is a specification, reference being had to the accompanying drawing, forming part thereof.

Fig. 1 is a side elevation of a velocipede frame showing my new design.

Fig. 2 is a plan view of the frame.

Fig. 3 is a perspective view of the frame.

I claim:

The ornamental design for a velocipede frame as shown.

ROBERT J. RADER.
